CLAIM

The ornamental design for a cooling jacket for semiconductor device, as shown and described.

DESCRIPTION

FIG. 1 is a perspective view of front, top plan and right side of a cooling jacket for semiconductor device showing my new design;

FIG. 2 is a perspective view of rear, bottom and left side thereof;

FIG. 3 is a front view thereof;

FIG. 4 is a rear view thereof;

FIG. 5 is a top plan view thereof;

FIG. 6 is a bottom view thereof;

FIG. 7 is a left side view thereof;

FIG. 8 is a right side view thereof; and,

FIG. 9 is a cross-sectional view thereof taken along line 9-9 in FIG. 9 view.
